DISPLAY CABINET

Simon Malkin, New York, N. Y., assignor to
Malkin Inc., New York, N. Y., a corporation of
New York

Application January 28, 1954, Serial No. 28,713

Term of patent 3½ years

(Cl. D80—11)

To all whom it may concern:

Be it known that I, Simon Malkin, a citizen of the United States, residing at New York, in the county of New York, and State of New York, have invented a new, original, and ornamental Design for a Display Cabinet, of which the following is a specification, reference being had to the accompanying drawing, forming part thereof.

In the drawing:

Fig. 1 is a front perspective view of a display cabinet, showing my new design;

Fig. 2 is a front perspective view of a slide display unit of the cabinet;

Fig. 3 is a top plan view of Fig. 1;

Fig. 4 is a vertical sectional view of the display cabinet, taken on line 4—4 of Fig. 1; and
Fig. 5 is a rear perspective view of Fig. 1.

I claim:

The ornamental design for a display cabinet, as shown.
